US00D750669S

(12) **United States Design Patent**
Cranfill et al.

(10) **Patent No.:** US D750,669 S
(45) **Date of Patent:** ** Mar. 1, 2016

(54) **DISPLAY SCREEN OR PORTION THEREOF
WITH GRAPHICAL USER INTERFACE**

(71) Applicant: **Apple Inc.**, Cupertino, CA (US)

(72) Inventors: **Elizabeth Caroline Cranfill**, San Francisco, CA (US); **Mikio Inose**, Cupertino, CA (US); **Stephen O. Lemay**, San Francisco, CA (US)

(73) Assignee: **Apple Inc.**, Cupertino, CA (US)

(**) Term: **14 Years**

(21) Appl. No.: **29/484,827**

(22) Filed: **Mar. 13, 2014**

Related U.S. Application Data

(63) Continuation of application No. 29/434,750, filed on Oct. 16, 2012, now Pat. No. Des. 701,234, which is a continuation of application No. 29/416,023, filed on Mar. 16, 2012, now Pat. No. Des. 669,091, which is a continuation of application No. 29/354,643, filed on Jan. 27, 2010, now Pat. No. Des. 658,195.

CLAIM

The ornamental design for a display screen or portion thereof with graphical user interface, as shown and described.

DESCRIPTION

The FIGURE is a front view of a display screen or portion thereof with graphical user interface showing our new design. The outermost broken lines in the FIGURE show a display screen or portion thereof, form no part of the claimed design.
